COLLAPSIBLE REEL

Maurice G. Steele, Rome, N.Y., assignor to Rome Cable Corporation, Rome, N.Y., a corporation of New York

Application April 2, 1956, Serial No. 575,526

4 Claims. (Cl. 242—115)

This invention relates to collapsible reels, spools and the like used for the packaging of wire and cable and the shipping of wire and cable. The term "reel" connotes end members or flanges which extend radially beyond a cross member or core intermediate the ends which provides the surface around which a length of wire or cable is wound. This cross member is referred to herein as a core or drum but it will be understood that it does not need to have a continuous surface and while usually cylindrical in form it is not necessarily so and can be polygonal in cross section. It will be further understood that a length of wire or cable can be wound directly around a drum or spool having very low end flanges or none at all.

An object of the invention is to provide a device of the above mentioned kind which is relatively inexpensive to manufacture and may be scrapped when the wire or cable has been unwound from it.

Another object of the invention is to provide such a device which will be automatically disassembled when a shipment of wire or cable has been unwound from it.

Another object of the invention is to provide a device of the above described kind which will have optimum strength and durability when wire or cable is wound on it but will suddenly lose its strength and collapse when the last turn of wire is removed, thus facilitating disposal of the elements comprising it.

The invention will best be understood if the following description is read in connection with the drawings, in which:

Figure 1 is a front elevation partly in section showing an assembly embodying the invention.

Figure 2 is a similar view showing a tripping lever actuatable to collapse the assembly.

Figure 3 is an end view of a number of staves of curved cross section which in one form of the invention are assembled around suitable backing means to provide a drum.

Figure 4 is a view similar to Figure 3 showing staves which are straight in cross section instead of curved as in Figure 3.

Figure 5 is a modification of the drum forming means shown in Figures 3 and 4 indicating a length of sheet material such for example as a strip of wood veneer which may be bent around backing means to provide a drum.

Figure 6 is a perspective view of a band for tightening the drum forming means against support means.

Figure 7 is an enlarged detail view partly in section of a portion of Figure 1 showing means for interengaging drum forming means and backing means.

Figure 8 is a perspective view of a clasp member for the band shown in Figure 6.

Figure 9 is a perspective view of a strut member which coacts with the clasp member shown in Figure 8 for tensioning and releasing the band.

2

Figure 10 is a diagrammatic view illustrating the first step in the use of the clasp and strut members for tightening the band.

Figure 11 is a view similar to Figure 6 showing the position of the clasp and strut members after they have placed the band under tension.

Figure 12 is a view in perspective of a tripping lever for unclasp the clasp means, and

Figure 13 is a view similar to Figures 10 and 11 illustrating the raising of the strut and clasp members by the tripping lever to thereby release the band from tension and initiate collapsing of the assembly.

This invention comprises positioning means, forming a core or drum around which a length of wire or cable may be wound, against backing means and holding the core or drum against the backing means by releasable means so that the assembly may be readily collapsed and disassembled. In the embodiment of the invention illustrated herein the assembly of backing means 10 and core or drum 12 is disposed between two ends 14 forming a reel which when assembled has the general appearance of the non-collapsible reels, which are used at the present time for packaging and shipping lengths of wire and cable. Such non-collapsible reels are stoutly made and are conventionally returned by the purchaser of the wire or cable to the manufacturer to be used again and again. These non-collapsible reels are not only costly to make but costly to return for they are bulky and occupy costly shipping space.

30 A drum or spool may be formed by a number of staves 16 or 16a, or by a flexible sheet member such as, member 18 illustrated in Figure 5.

As illustrated in Figures 1 and 7 the backing means 10 is provided by disks 20, the peripheral edges of which are spaced inwardly from the end members 14 respectively. The periphery of the disks 20 is defined by an inwardly inclining angular edge 22. If staves 16 or 16a are employed they are provided on the under side adjacent their ends respectively with the clamping transverse grooves 24 adapted to receive the peripheral edge of the backing disks 20 respectively. Preferably the clamping transverse grooves 24 are substantially the same shape as the peripheral edge of the backing disks 20 but slightly wider providing a slight clearance for ease in assembling the staves against the backing disks. If the drum is formed of a unitary flexible sheet such for example as a sheet of wood veneer, it will be provided with the transverse grooves 24 adjacent its lateral edges and will be bent around the backing means 20 and assembled against them in the same manner as the staves.

50 It will be understood that in some instances, as for example for a short length of wire, a drum or core may be formed using backing means, which may be similar to disks 20 and employed without end members or with end members of only slightly greater diameter than the diameter of the drum. It is preferred however to use end members of substantially greater diameter than the drum, particularly where the wire or cable is long enough to form a number of layers or turns around the drum. 60 Such end members may be of wood, metal, fiber or any suitable and preferably inexpensive material.

The drum forming means whether it be the staves 16 or 16a or a unitary flexible sheet member 18, is preferably grooved with the circumferential groove 26 to receive the flexible band 28, which, when tightened, serves to hold the drum forming means tightly against the periphery of the backing disks 20. The term "band" is used broadly to include a length of flexible material of any cross section but a flat band such as is illustrated in Figure 6 is preferred. The ends of this band are overturned outwardly forming the hook like ends 30. The band is made of such length that when it is wrapped

around the staves or other drum forming means, the overturned ends 30 remain a short distance apart as illustrated in Figure 6. The fastening of the band is accomplished by means of a clasp member 32, Figure 8, and a strut member 36, Figure 9, which cooperate with one another and the ends of band 28 to produce a toggle joint clamp or clasp. The clasp member 32 is about twice the length of the intervening space between the overturned ends of the band and is itself provided with overturned ends 34 similar to the ends 30 of the band. Preferably the clasp member 32 is made of heavier metal than band 28 to make it rigid and the strut member 36 is a short rectangular rigid member which is slightly greater in length than half the distance between the overturned ends of the band when the band is placed around the drum forming means with the latter positioned against the backing means of the assembly.

The construction and functioning of the clasp or clamping means are shown in Figures 10, 11 and 13. In assembling the reel the staves or other drum forming means are placed around the backing disks 20 with the edge of the disks received in the transverse grooves 24 and the band 28 is drawn around the external face of the drum forming means, in the groove 26, until the ends are adjacent one another with the overturned end portions 30 facing outwardly as illustrated in Figure 6. The clasp member 32 with its overturned ends 34 facing downwardly is now engaged with one end of the band by hooking one of its overturned end portions 34 under one overturned end 30 of the band, and the strut member 36 is then inserted between the other end 30 of the band and the other overturned end 34 of clasp member 32, as is illustrated in Figure 10. Preferably the strut member 36 is inserted between the band and clasp ends while the clasp member is elevated from the band on one end, as shown in Figure 10, and is then rotated downwardly around its end which is engaged directly with the band. It will be seen that during this movement the strut member 36 will exert force in one direction directly against one end of the band and in the other direction indirectly against the other end of the band through member 32, thus drawing the two ends of the band toward one another and causing the staves or other drum forming means to be held firmly against the periphery of the backing disks 20.

When the strut member 36 and the clasp member 32 are directly superimposed over the band 28 as illustrated in Figure 11 the band is locked around the drum forming means in tension and the force which strut member 36 applies to the clasp member 32 serves to prevent inadvertent unlocking movement of the clasp means. It will be understood that as wire or cable is wound around the drum portion of the assembled reel the turns of the wire will supplement the action of band 28 and thus contribute to imparting to the assembly great strength and rigidity.

For unlocking the clasp means to loosen the band and permit the assembly to be disassembled when the last turn of wire or cable is unwound from the reel a tripping lever, illustrated in Figure 12, is provided. This tripping lever comprises an intermediate portion 40 which desirably may be round in cross section; the end portion 38 which extends substantially at right angles to portion 40 and is adapted to be inserted under the strut member 36, between the strut member and the outer surface of band 28, when the strut member 36 and the clasp member 32 are pivoted down to the position shown in Figure 11, and the end portion 42 which is angularly disposed with respect to the middle portion 40 and is curved to conform to the curvature of the drum surface. As is best seen in Figure 2, the drum forming means is provided with a groove 44 extending parallel to the axis of the drum and communicating at one end with the groove 26, and the intermediate portion 40 of the tripping lever is placed in this groove with the flattened end 38

positioned over the band 28 and under the strut member 36. The intermediate portion 40 of the tripping lever is held loosely in the groove 26 by cover plate 46, which may be of any suitable material such for example as heavy cardboard, fiber or metal, and coats with groove 44 to provide a bearing within which the tripping lever may rotate.

The end of the wire or cable, which is to be wound on the reel in a direction opposite to the direction in which the end portion 42 of the tripping lever is disposed, is connected in any suitable way to the free end of the end portion 42. The wire is then wound around the drum of the reel in successive layers of turns. When the wire or cable is unwound from the drum the pull exerted by the last turn of wire or cable will raise the arm 42 of the tripping lever from the surface of the drum causing its intermediate portion 40 to be rotated within groove 44 and elevating the end 38 which thus prys up the strut member 36 as illustrated in Figure 13, unclamping the clasp means and loosening the band 28. The staves 16, 16a or other drum forming means are thus freed from the pressure holding them against the backing disks 20, or other backing means, causing the whole structure to suddenly collapse and be disassembled.

It is contemplated that the structure described above, because of its inexpensiveness and the cost of returning reels of the type now employed, will ordinarily be used only once, and the parts disposed of as soon as the wire or cable thereon has been unwound. However, the parts of a collapsed reel can of course be reassembled. For example they could be returned disassembled to the wire manufacturer by a user and the transportation costs for shipping the disassembled parts would be materially less than for shipping a non-collapsible reel.

There has thus been provided an invention in which the objects enumerated above have been embodied together with many practical advantages.

What I claim is:

- 40 1. A collapsible reel for packaging wire or cable comprising two spaced backing disks, a number of staves assembled against said disks to provide a core around which to wind a wire or cable, a flexible band extending around the core including toggle clasp means interengaging the ends of the band and movable between closed position, in which it tensions the band and a portion of it closely overlies the band, and open position in which the band is relieved of tension and said portion is elevated from the band and angularly related to it, and means mounted on the core and rotatable around an axis parallel to the axis of the core having a portion extending under said clasp and a portion extending at right angles to the axis of the core and engageable with the trailing end of said wire or cable.
- 45 5. A collapsible device for packaging wire or cable comprising two spaced backing members, a plurality of core forming members, and a flexible band extending around said core forming members to bind them against said backing means, including folding toggle clasp means for interengaging the ends of the band and movable between folded position for tensioning said band around the core forming members to unfolded inactive position, and a tripping lever, mounted on the surface of the core for rotation around an axis parallel with the axis of the core and having a body portion, a head portion, and a third portion engageable with the trailing end of a wire or cable which is wrapped around the core, means for rotatably mounting the body portion on the surface of the core with its axis parallel to the axis of said core, said head portion being angularly disposed with respect to the body portion and extending under the folded clasp means, said third portion being angularly disposed with respect to said body portion and substantially parallel to said head portion.
- 50 6. A collapsible device for packaging wire or cable comprising two spaced backing members, a plurality of core forming members, and a flexible band extending around said core forming members to bind them against said backing means, including folding toggle clasp means for interengaging the ends of the band and movable between folded position for tensioning said band around the core forming members to unfolded inactive position, and a tripping lever, mounted on the surface of the core for rotation around an axis parallel with the axis of the core and having a body portion, a head portion, and a third portion engageable with the trailing end of a wire or cable which is wrapped around the core, means for rotatably mounting the body portion on the surface of the core with its axis parallel to the axis of said core, said head portion being angularly disposed with respect to the body portion and extending under the folded clasp means, said third portion being angularly disposed with respect to said body portion and substantially parallel to said head portion.
- 55 7. A collapsible device for packaging wire or cable comprising two spaced backing members, a plurality of core forming members, and a flexible band extending around said core forming members to bind them against said backing means, including folding toggle clasp means for interengaging the ends of the band and movable between folded position for tensioning said band around the core forming members to unfolded inactive position, and a tripping lever, mounted on the surface of the core for rotation around an axis parallel with the axis of the core and having a body portion, a head portion, and a third portion engageable with the trailing end of a wire or cable which is wrapped around the core, means for rotatably mounting the body portion on the surface of the core with its axis parallel to the axis of said core, said head portion being angularly disposed with respect to the body portion and extending under the folded clasp means, said third portion being angularly disposed with respect to said body portion and substantially parallel to said head portion.
- 60 8. A collapsible device for packaging wire or cable comprising two spaced backing members, a plurality of core forming members, and a flexible band extending around said core forming members to bind them against said backing means, including folding toggle clasp means for interengaging the ends of the band and movable between folded position for tensioning said band around the core forming members to unfolded inactive position, and a tripping lever, mounted on the surface of the core for rotation around an axis parallel with the axis of the core and having a body portion, a head portion, and a third portion engageable with the trailing end of a wire or cable which is wrapped around the core, means for rotatably mounting the body portion on the surface of the core with its axis parallel to the axis of said core, said head portion being angularly disposed with respect to the body portion and extending under the folded clasp means, said third portion being angularly disposed with respect to said body portion and substantially parallel to said head portion.
- 65 9. A collapsible device for packaging wire or cable comprising two spaced backing members, a plurality of core forming members, and a flexible band extending around said core forming members to bind them against said backing means, including folding toggle clasp means for interengaging the ends of the band and movable between folded position for tensioning said band around the core forming members to unfolded inactive position, and a tripping lever, mounted on the surface of the core for rotation around an axis parallel with the axis of the core and having a body portion, a head portion, and a third portion engageable with the trailing end of a wire or cable which is wrapped around the core, means for rotatably mounting the body portion on the surface of the core with its axis parallel to the axis of said core, said head portion being angularly disposed with respect to the body portion and extending under the folded clasp means, said third portion being angularly disposed with respect to said body portion and substantially parallel to said head portion.
- 70 10. A collapsible device for packaging wire or cable comprising two spaced backing members, a plurality of core forming members, and a flexible band extending around said core forming members to bind them against said backing means, including folding toggle clasp means for interengaging the ends of the band and movable between folded position for tensioning said band around the core forming members to unfolded inactive position, and a tripping lever, mounted on the surface of the core for rotation around an axis parallel with the axis of the core and having a body portion, a head portion, and a third portion engageable with the trailing end of a wire or cable which is wrapped around the core, means for rotatably mounting the body portion on the surface of the core with its axis parallel to the axis of said core, said head portion being angularly disposed with respect to the body portion and extending under the folded clasp means, said third portion being angularly disposed with respect to said body portion and substantially parallel to said head portion.
- 75 11. A collapsible device for packaging wire or cable comprising two spaced backing members, a plurality of core forming members, and a flexible band extending around said core forming members to bind them against said backing means, including folding toggle clasp means for interengaging the ends of the band and movable between folded position for tensioning said band around the core forming members to unfolded inactive position, and a tripping lever, mounted on the surface of the core for rotation around an axis parallel with the axis of the core and having a body portion, a head portion, and a third portion engageable with the trailing end of a wire or cable which is wrapped around the core, means for rotatably mounting the body portion on the surface of the core with its axis parallel to the axis of said core, said head portion being angularly disposed with respect to the body portion and extending under the folded clasp means, said third portion being angularly disposed with respect to said body portion and substantially parallel to said head portion.

comprising two spaced backing means, a plurality of core forming members assembled against said backing means to provide a core around which to wind a wire or cable, said core forming means having transverse grooves in their outer surfaces respectively, said grooves being aligned circumferentially of the core, a flexible band extending around the core and disposed in the circumferential groove thus provided, said band including toggle clasp means interengaging the ends of said band and movable between folded position for tensioning said band around the core forming members to unfolded inactive position, a groove in the exterior surface of one of said core forming members extending parallel to the axis of the core and opening at one end into the circumferential groove, and a tripping lever comprising, a body portion, 10 a head portion and an attachment portion for engagement with the trailing edge of the wire or cable wrapped around the core, means for rotatably mounting said body portion in the axially extending groove, said head portion being disposed substantially at right angles to the body portion within the circumferential groove and projected under said folding clasp, and said attachment portion being also disposed substantially at right angles to the body portion and substantially parallel to the head portion and extending from said axial groove in a direction 15 around the periphery of the core and opposite to the

5 unwinding direction of the trailing end of the wire or cable to which it is attached, whereby, as the trailing end of the wire or cable leaves the core it applies pressure on said attachment portion which serves as a crank arm

10 to rotate the body portion and to elevate the head portion thus raising and unfolding the clasp.

4. The device claimed in claim 1 in which the clasp means comprises, a clasp member pivotally connected to the band at one end, and a strut member interposed between the other end of said clasp member and the other end of the band and pivotally related to the ends of the clasp and band respectively between which it is interposed, said clasp member being longer than the distance between the ends of the band when the latter is tightly wrapped around the core, and said strut being slightly greater in length than the distance by which the clasp exceeds the distance between the ends of the band.
